UNITED STATES PATENT OFFICE

172,198

DISPENSING CONTAINER FOR SAW BLADES

George Scharfenberg, Glen Lake, Minn., assignor
to Continental Machines, Inc., Savage, Minn.,
a corporation of Minnesota

Application April 13, 1953, Serial No. 24,473

Term of patent 14 years

(Cl. D58—12)

To all whom it may concern:

Be it known that I, George Scharfenberg, a citizen of the United States, residing at Glen Lake, in the county of Hennepin and State of Minnesota, have invented a new, original, and ornamental Design for a Dispensing Container for Saw Blades, of which the following is a specification, reference being had to the accompanying drawing, forming part thereof.

Figure 1 is a front view of a dispensing container for saw blades embodying my new design;

Figure 2 is a back view thereof; and

Figure 3 is a sectional view taken through Figure 1 on the plane of the line 3—3.

I claim:

The ornamental design for a dispensing container for saw blades, as shown.
